(57) **CLAIM**

The ornamental design for a ceiling fan with sports items, as shown and described.

DESCRIPTION

FIG. 1 is a bottom perspective view of a ceiling fan with sports items, showing my new design;

FIG. 2 is a top perspective view thereof;

FIG. 3 is a front view of FIG. 1;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Portions of the ceiling fan shown in broken lines form no part of the claimed design.

1 Claim, 8 Drawing Sheets**FIG. 2**

FIG. 3

FIG. 4

FIG. 5

FIG. 6

FIG. 7

FIG. 8
